UNITED STATES PATENT OFFICE.

GEORGE GRONELL, OF NEW YORK, N. Y., ASSIGNOR TO PASQUALE GALASSI, OF NEW YORK, N. Y.

APPARATUS FOR FORMING SHEET-METAL ARTICLES.

Application filed February 10, 1926. Serial No. 37,234.

My invention relates to apparatus for forming articles of sheet materials, and more particularly for forming sheet metal strips such as shown in United States patent to 5 Galassi No. 1,377,675, dated May 10, 1921, for use in expansion joints of paving material.

The principal object of the invention is to provide efficient apparatus whereby such 10 articles may be made quickly and at a low cost.

Other objects, features and advantages will appear more fully in the following description and appended claims.

15 The accompanying drawings forming a part of this specification illustrate one embodiment of the invention.

In the drawings,

Figure 1 is a plan view of the apparatus. 20 Figure 2 is an end view of same.

Figure 3 is a front elevation of same.

Figures 4, 5 and 6 are sections taken respectively on the lines 4-4, 5-5 and 6-6 of Fig. 1; and

25 Figure 7 is a perspective view of one form of strip adapted to be formed by the apparatus.

The strips *a* shown in Fig. 7 are adapted to be embedded in a vertical position between 30 various sections of paving material; so that in case of contraction of the paving material it will yield along the strips so as to avoid objectionable breaks in the paving material. The strips are preferably formed 35 of sheet metal and are provided with tabs or flanges *b*, *c* extending outwardly in opposite directions from the body of the strip, these tabs or flanges being adapted to be embedded in the paving material so as to 40 hold the strip in place in case of contraction of the paving material away from the body of the strips. The apparatus shown in the drawings is adapted to form the tabs or projections *b*, *c* upon the strips *a*.

45 For holding the strips in position, the apparatus comprises jaws 1 and 2, the jaw 1 being secured in fixed position upon base 3 and the jaw 2 being movable upon said base in a horizontal direction toward and 50 away from the jaw 1. The base 3, as shown, is supported upon standards 4. For moving the jaw 2 towards the jaw 1 into clamping relation with respect to the same, the apparatus shown comprises cams or eccentrics 5 bearing against the outer face of jaw 2 and

supported for pivotal movement about a vertical axis by the base 3 and bridge-like members 6 (see Fig. 1). Two of these members 6, as shown in Fig. 1, are arranged at the respective ends of the machine and are secured to the tops of the fixed jaw 1 and bars 7 and 8 which extend parallel to the jaws on opposite sides thereof respectively and are secured to the base 3 (as shown in Fig. 4). To the upper ends of the cams 5 are secured cranks 9 which are connected at their free ends by a link 10, so that all of the cams may be operated in unison to move the jaw 2 into clamping relation throughout the length of the jaws. One 70 of the cranks 9 is formed with an extension 11 in the nature of a handle so as to facilitate the operation of the cranks 9 to effect movement of the jaw 2 towards the jaw 1. Springs 12 (Fig. 4) tend to move the jaw 2 away from the jaw 1. One or more strips 75 *a* are adapted to be held between the jaws 1 and 2, their downward movement being limited by stops or supports 14 supported by the bars 7 and 8. 80

For forming the projections *b*, *c* on the strips, the apparatus comprises a plurality of punches 15, alternate punches operating from opposite sides of the strips *a*. In the form of invention shown, a plurality of 85 punches operate from each side of the strip. These punches each comprises a plunger 16 (see Figs. 1 and 4) which is supported for horizontal movement at right angles to the jaws 1 and 2 by the bars 1 and 7 or 2 and 8, 90 depending upon which side of the strip the plunger is arranged. The plungers 16 coat with dies 17 arranged on the opposite side of the strips *a*. The lower face of each plunger has a slight clearance with respect 95 to the corresponding face of the die; so that as the plunger forces the sheet material into the die, it will not completely sever the part of the material engaged by the punch from the rest of the material but will merely fold 100 over that part of the material so as to form a tab or flange *b* or *c*. The side faces of the plungers fit fairly accurately against the side faces of the die so as to sever the side edges of the flange portions *b* or *c* from the body 105 of the material. For operating the various plungers on each side of the apparatus in unison they are connected to cams 18 secured to shafts 19, which are respectively arranged on opposite sides of the clamping jaws 1 and 110

2 in parallel relation to said jaws. The shafts 19 are arranged to be rotated in unison in opposite directions by intermeshing gears 20 and 21 secured to said shafts respectively. As shown in the drawings, the power is supplied from electric motor 22, the shaft of which is connected by worm 23 with worm wheel 24 which is rotatably mounted upon one of the shafts 19 adjacent the gear 21. To permit operation of the motor without operation of the sheet forming apparatus, a clutch is provided between worm wheel 24 and the shaft 19 by which it is supported. Any suitable form of clutch may be used, the 15 clutch shown having a clutch member 25 secured to the shaft 19 and a movable clutch member 26 fitting for longitudinal movement into a recess in the member 25 and adapted to engage a recess 27 in the hub of 20 the worm wheel 24. A spring 28 tends to hold the clutching member 26 in clutching relation to the worm wheel 24. The member 26 is however normally held unclutched from the worm wheel by means of the upper 25 wedge-shaped end 29 of rod 30, the lower end of which is connected to an operating pedal 31. A spring 32 arranged between the guide 33 and a shoulder on the rod 30 tends to hold said rod and the lever 31 in elevated 30 position with the clutch disengaged. To permit clutching of the shaft 19 to the worm wheel 24, lever 31 is depressed thereby moving the rod 29 out of obstructing relation to the clutch member 26 and permitting the 35 spring member 28 to force the clutch member 26 into operative relation to the worm wheel. When the pedal 31 is released the spring 32 moves the rod upwardly whereby the wedge-shaped upper end of the said rod 40 moves the clutch member 26 into inoperative or unclutching position.

It may at times be desired to operate only the punches on one side of the apparatus so as to form the tabs or flanges only on one 45 face of the strips. To this end I have provided a clutch 34 which is movable by a lever 35 to operatively disconnect the gear 20 from the shaft 19 by which it is supported.

To achieve the removal of the punch strip 50 from the clamping jaws the apparatus includes ejecting means for the strip. The ejecting means shown comprises a plurality of ejector pins 36, the lower ends of which are formed with loops 37 whereby the said pins are movably supported upon a bar 38. By moving the pins 36 along the bar 38 they 55 may be positioned in desired relation under the lower edge of the strips *a*. The bar 38 is, as shown, supported by parallel links 39 and 40 and is movable upwardly with the ejector pins by means of lever 41 which engages a projection 42 on the bar 38 and is provided with an arm 43 whereby it may be readily operated by foot. Movement of the 60 lever 41 about its axis effects movement of 65

the links 39 and 40 about their axes, the bar 38 and pins 36 being moved upwardly during such movement. A handle 44 secured to the bar 38 may also be used to effect the desired upward movement of the bar.

In operation one or more strips are placed 70 between the jaws 1 and 2, the lever 11 then being operated to shift the jaw 2 to clamp the strips between the jaws 1 and 2. The motor 22 being in operation, the worm 75 gear 24 operates idly. By depressing the lever 31 the said worm gear is clutched to the shaft 19 supporting the same, whereupon both shafts 19 are operated, rotating the cams 18 and operating the punches 80 to form the projections *b* and *c* upon the strips. After the strips have been so formed the pedal 31 is released to stop operation of the punches, and jaw 2 is moved to open position by the lever 11. The ejector 85 bar 38 is now elevated either by the lever 44 or the lever 43, whereupon the ejector pins lift the formed strip from between the jaws. In case it is desired to form a projection on 90 only one side of the sheet, the clutch 34 is released by the lever 35 during the forming operation.

While I have shown one embodiment of my invention, it is to be understood that I am not limited thereto. Furthermore while 95 I have shown and described the apparatus for forming a certain kind of strip, it is understood that the apparatus may be used for forming other kinds of articles.

Having thus described my invention, what I claim as new and desire to secure by Letters Patent is:

1. The combination of a support for an article of sheet material, a plurality of punches having movable plungers arranged adjacent each face of the article for forming on said article while carried by said support projections extending outwardly from the article in opposite directions, means for simultaneously operating said punches, and means for rendering the plungers adjacent one face of the article inoperative while permitting operation of the plungers adjacent the other face of the article.

2. The combination of a support for an article of sheet material, means for forming on said article while carried by said support projections extending outwardly from the article in opposite directions, and means for ejecting the article from the support, said ejecting means comprising a plurality of members arranged to engage the article at different places and means for simultaneously moving said members to lift the article 125 relatively to said support.

3. The combination of a support for an article of sheet material, a plurality of punches having movable plungers arranged adjacent each face of the article for form-

ing on said article while carried by said support projections extending outwardly from the article in opposite directions, means for simultaneously operating said 5 punches, and means for ejecting the article from the support, said ejecting means comprising a plurality of members arranged to engage the article at different places, and means for simultaneously moving said members to lift the article relatively to said support.

4. The combination of a support for an article of sheet material, a plurality of punches having movable plungers arranged 15 adjacent each face of the article for forming on said article while carried by said support projections extending outwardly from the article in opposite directions, means for simultaneously operating said punches, and 20 means for ejecting the article from the support, said ejecting means comprising a plurality of pins, a member on which said pins are loosely mounted to permit change of the position thereof relatively to the length of 25 the article, and a lever for moving said member to cause said pins to lift the article relatively to the support.

5. The combination with a clamp comprising a fixed jaw, a movable jaw, yielding 30 means tending to move said movable jaw away from said fixed jaw, and means for forcing said movable jaw into clamping position, of means for operating from opposite directions on an article carried by said 35 clamp, the actuation of said means for forcing said movable jaw into clamping position being entirely separate and distinct from the actuation of said last mentioned means.

6. The combination with a clamp comprising a fixed jaw, a movable jaw, yielding 40

means tending to move said movable jaw away from said fixed jaw, and means for forcing said movable jaw into clamping position, of means for operating from opposite directions on an article carried by said 45 clamp to form oppositely disposed flanges on the article, the actuation of said means for forcing said movable jaw into clamping position being entirely separate and distinct from said last mentioned means. 50

7. The combination of a fixed jaw, a second jaw, means for moving said second jaw horizontally into or out of clamping relation to said fixed jaw, and punches arranged to form a plurality of oppositely directed 55 flanges on an article of sheet material supported between said jaws, the actuation of said means for moving said second jaw being entirely separate and distinct from the actuation of said punches. 60

8. The combination of a support, means for operating from opposite directions upon an article carried by said support, a single source of power in driving relation to both of said means, and means whereby the 65 means operating from one direction may be disconnected from said source without disconnecting from said source the means operating in the opposite direction.

9. The combination of a fixed jaw, a second jaw, means for moving said second jaw horizontally into or out of clamping relation to said fixed jaw, punches arranged to form a plurality of oppositely directed 70 flanges on an article of sheet material supported between said jaws, and means for ejecting the article from between said jaws. 75

In testimony whereof, I have signed my name to this specification.

GEORGE GRONELL.
